UNITED STATES PATENT OFFICE.

LAURA K. H. THOMSEN, OF SAN FRANCISCO, CALIFORNIA.

DANCING TOY.

Application filed April 19, 1926. Serial No. 102,853.

This invention relates to dancing toys and particularly to soft stuffed animals having soft stuffed limbs sewed thereto in a manner forming pivotal connections, permitting lateral swinging movement of the limbs to simulate a grotesque dance when the toy is jerked quickly on a supporting cord. It is the primary object of my invention to provide an improved dancing toy of this type.

10 My invention relates particularly to stuffed animal dancing toys which can be made in the home by needle work. The bodies, which can be made to represent various animals and figures, are formed entirely 15 from soft fabric material and the legs, arms, and head are attached thereto by sewing, in a manner forming pivotal seam connections permitting lateral swinging movement. The legs can also be jointed by sewing a seam 20 thereacross. The dancing movement is conveyed to the toy by an inelastic cord, all of which will be hereinafter described.

The toy is so constructed that it can readily be made in the home and provide attractive needle work for the children and even the older daughters of the family. My improved toy can be manufactured and sold as a complete article, or the parts necessary to make the toy may be formed and sold. 30 The latter procedure is preferable. The several parts necessary to construct the toy are formed and placed in an envelope which is made an article of sale. In addition to having all these necessary parts, the envelope 35 also contains full instructions for making the toy. The adaptability of the toy to this method of sale and distribution, is a very desirable feature of the invention.

In the accompanying drawings, I have illustrated two examples of animal toys embodying my invention, but it will be understood that the invention can be otherwise embodied and that the drawings are not to be construed as defining or limiting the scope 40 of the invention, the claims appended to this specification being relied upon for that purpose.

Referring to the figures of the drawing: Figure 1 illustrates a black lady "shimmy" doll, embodying my invention.

50 Figure 2 illustrates my invention embodied in a dancing mule.

The toy illustrated in Fig. 1 is a black lady "shimmy" doll having a small slender body 1 and long slender arms 2 and legs 3. The arms are unjointed and the legs are

jointed at 4. The arms and legs are pivotally secured to the body for lateral swinging movement by being sewed thereto and the joint 4 is formed by sewing in like manner. 60 The extremities of the legs are weighted by clogs 5, whereby to aid the dancing movement of the toy.

The head 6 is relatively large and supported on a relatively long neck 7. The 65 hair 8 may be made of yarn and the eyes and mouth may be embroidered in suitable colors. The hips 9 are relatively wide, substantially the width of the body, and a bright colored skirt 10 may be placed thereover. 70 The toy is adapted to be supported on an inelastic cord 11 attached centrally to the rear of the body at the base of the neck.

The construction and supporting of the doll is such that it will simulate a grotesque 75 dance and cause great amusement and merriment when manipulated on the cord 11. The cord is so attached that the doll assumes its normal upright position when supported thereby. By dancing the doll on the cord 80 by short quick jerks, its arms and legs are caused to flop about in a manner simulating a very odd dance. The arms being unjointed, will flop upwardly and outwardly and the legs being jointed, will bow outwardly 85 as illustrated in dash lines. The clogs for the feet aid considerably in this movement and the engagement of these clogs with the floor simulates a clog dance.

In Fig. 2, I have illustrated my toy as 90 embodied in a dancing mule. The general construction and performance of this toy is similar to that shown in Fig. 1. The body 12 has a pair of unjointed hind legs 13 sewed for lateral pivotal movement thereto at 14 95 and a pair of fore legs 15 sewed thereto in like manner and provided with a sewed pivotal joint 16. Clogs 17 are sewed to the ends of the legs by thread extending through holes 18.

The head 19 of the mule may be provided with ears 20 sewed thereto for pivotal flopping movement in like manner as the legs. The tail may be formed from a twisted cord 21. The supporting and operating cord 22 105 is attached to the mule at the center of the back in a position which balances the body and its parts horizontally when supported thereon.

The operation and performance of the 110 dancing mule is similar to that of the doll shown in Fig. 1. When slightly raised off

the floor by the cord 22 and given quick short jerks, the hind legs flop or kick outward about the pivots 14. The fore legs flop about the body pivots and bend at the intermediate joints 16 and the ears flop in like manner, as illustrated in dash lines in Fig. 2. The clogs 17 aid considerably in the effect produced. It will be understood that the various movements cannot be completely illustrated in the drawing, but that the general construction is such that the body is well balanced and moves about rather gracefully, while the hind legs kick outwardly and laterally and the fore legs swing and bend outwardly in a very peculiar but pleasing manner. This toy also gives the appearance that the mule rears, bucks and kicks sideways.

It will of course be understood that my toy can be made to represent many different figures in addition to those illustrated in the drawing.

In all these toys, the dancing movement is conveyed by the proper attachment of the inelastic cord to the toy and the proper connection and jointure of the body and limbs. The position of the point of attachment of the cord and the weighting of the feet are so combined as to produce new and novel movements for each toy, separate and distinct from any other of the toys. It is this combination of a soft stuffed body, soft stuffed members hinged thereto, weights attached to the extremities of such members, the direction and position of the hinges, and the location of the point of suspension, which comprises the particular novelty of my invention. Also, the adaptability of the same for sale in package form for needle work is of particular value.

Having thus described my invention, what I claim is:

1. A dancing toy comprising a soft stuffed animal body, soft stuffed limbs sewed there-

to in a manner forming pivotal connections 45 permitting lateral swinging movement of the limbs, weights attached to the extremities of certain of the limbs, and an inelastic cord attached to the body in a position to support the body and limbs in the natural 50 position which they normally occupy, quick jerking movement of the cord when supporting the body being adapted to cause the limbs to flop laterally about their pivots to simulate a grotesque dance. 55

2. A dancing toy comprising a soft stuffed animal body, soft stuffed limbs sewed thereto in a manner forming pivotal connections permitting lateral swinging movement of the limbs, certain of the limbs having intermediate portions providing flexible joints, weights attached to the extremities of certain of the limbs, and an inelastic cord attached to the body in a position to support the body and limbs in the natural position 60 which they normally occupy, quick jerking movement of the cord when supporting the body being adapted to cause the limbs to flop laterally about the said pivotal connections and joints to simulate a grotesque 65 dance. 70

3. A dancing toy comprising a soft stuffed animal body, two pairs of soft stuffed limbs secured thereto in a manner forming pivotal connections permitting lateral swinging 75 movement of the limbs, one pair of limbs having intermediate sewed portions providing flexible joints, weights attached to the extremities of certain of the limbs, and an inelastic cord attached to the body in 80 a position to support the body and limbs in the natural position which they normally occupy, quick jerking movement of the cord when supporting the body being adapted to cause the limbs to flop laterally about the 85 said pivotal connections and joints to simulate a grotesque dance.

LAURA K. H. THOMSEN.
